UNITED STATES PATENT OFFICE

2,352,890

COMBINED WRITING PAPER AND ENVELOPE

Bertha Foreman, Harlowton, Mont.

Application August 11, 1942, Serial No. 454,414

1 Claim. (Cl. 40—154)

The present invention relates to new and useful improvements in combined writing paper and envelopes, in which the writing paper is adapted to be folded to form the envelope, and an important object of the present invention is to provide means for mounting a picture or photograph on the paper to be enclosed in the envelope and also embodying means forming part of the envelope to support the picture in a position for display purposes.

A further object is to provide an article of this character of simple and practical construction, which is neat and attractive in appearance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like reference numerals refer to like parts throughout, and in which—

Figure 1 is a plan view of the rear of the folded envelope in position for mailing.

Figure 2 is a sectional view taken on a line 2—2 of Figure 1.

Figure 3 is a plan view on a reduced scale of the sheet of paper showing the picture frame and with one edge partly folded.

Figure 4 is a plan view of the rear of the folded envelope showing the hanger and

Figure 5 is a plan view on a reduced scale with the side flaps of the paper folded inwardly on the body of the envelope.

Referring now to the drawings in detail the numeral 5 designates a sheet of writing paper generally including a central section 6 which embodies an intermediate body 7 and upper and lower flaps 8 and 9 adapted for folding along the lines 10 and 11 respectively in overlapping relation on the body 7.

The upper edge of the upper flap 8 is provided with a gummed tab 12 and the lower edge of the lower flap 9 is provided with a gummed tab 13. The flaps 8 and 9 are formed with parallel slits 14 and 15 respectively adapted to receive the tabs 12 and 13 when the flaps are folded.

The upper flap 8 is also provided with slits 16—16 extending inwardly from one edge to form tabs 17—17 adapted to enter spaced parallel slits 18—18 formed in the lower flap 9.

Side flaps 19—19 are connected at the respective side edges of the body 7 by fold lines 20—20, each side flap including upper and lower flaps 21—21 connected to the intermediate flap 19

along fold lines 22—22, the flaps 21—21 being free of the adjacent flaps 8 and 9 and adapted to fold upon each other on the intermediate flap 19, as shown in Figure 3, and the flaps 19 are then adapted to fold inwardly on the body 7, after which the flaps 8 and 9 may be folded to cover the side flaps.

The inner surface of the paper including the flaps 19 and 21 may be ruled or otherwise utilized for writing purposes.

A paper frame 23 having a central opening 24 is cemented on the body 7 and between the frame and the body is positioned a picture or photograph 25 provided with a protective transparent cover sheet 26, the frame and picture likewise being enclosed by the several flaps when the same are folded to form the envelope.

If desired, the flaps may be folded backwardly against the back of the body 7 and the tab 13 provided with an opening 27 and left out of its slit 14 to provide a hanger projecting from the rear of the envelope in the manner illustrated in Figure 4 for suspending the picture frame on a wall fastener (not shown).

25 The gummed tab 12 may be utilized to secure the several flaps in folded position for mailing and may be either inserted in the slit 15 or adhesively secured to the back of the folded envelope, if desired.

30 In the use of the article, a message may be written on either or both sides of the flaps 19 and 21 which are then folded upon themselves, as shown at the right side of Figure 3, and then folded inwardly over the picture 24. The flaps 35 8 and 9 are then folded upon the body 7 with the flap 8 outermost and the flaps secured by the gummed tab 12 or by inserting the tab 12 in the slit 15. The tabs 17 are also inserted in the slits 18, as shown in Figure 1, and the envelope is 40 ready for mailing.

The addressee of the envelope may reverse the manner of folding the flaps so as to fold the flaps 19 and 21 behind the picture and also by inserting the tab 13 outwardly through the slit 14 of 45 the flap 8, as shown in Figure 4, to use the tab 13 as a hanger to display the picture on a wall or other surface.

Having thus described my invention, what is claimed as new is:

50 An article of the class described comprising a sheet of writing paper including an intermediate section composed of a body portion having upper and lower flaps, side flaps at each side edge of the body portion, upper and lower flaps on said side flaps, a paper picture frame secured to the

body portion and adapted to receive a picture therein, said second-named upper and lower flaps being foldable upon the respective side flaps and said side flaps being foldable over either the front or back of the body portion, said first-named upper and lower flaps being foldable upon the folded side flaps in either folded position of the latter, horizontal slits in the first-named upper and lower flaps, tabs on the top and bottom

edges respectively of the first-named upper and lower flaps adapted for insertion in said slits, said first-named lower flap also having vertical slits therein, and horizontal tabs at the side edges of the first-named upper flap adapted for insertion in the vertical slits, one of said first-named tabs having an opening to provide a hanger for the folded article.

BERTHA FOREMAN.
